CLAIM

The ornamental design for a pendant, as shown and described.

DESCRIPTION

FIG. 1 is a perspective view of a pendant showing my new design;

FIG. 2 is a top plan view thereof;

FIG. 3 is a front elevational view thereof;

FIG. 4 is a left side elevational view thereof the right side elevational view being a mirror image;

FIG. 5 is a rear elevational view thereof; and,

FIG. 6 is a bottom plan view thereof.

The broken line showing of a partial jewelry chain and attaching element in FIGS. 1 through 5 is for illustrative purposes only and forms no part of the claimed design.
